UNITED STATES PATENT OFFICE.

BERRY A. BAXTER, OF MANSFIELD, OHIO.

STOVE-DOOR.

1,072,809.

Specification of Letters Patent. Patented Sept. 9, 1913.

Application filed December 6, 1912. Serial No. 735,290.

To all whom it may concern:

Be it known that I, BERRY A. BAXTER, a citizen of the United States of America, residing at Mansfield, in the county of Rich-
5 land and State of Ohio, have invented cer-
tain new and useful Improvements in Stove-
Doors, of which the following is a specifi-
cation.

This invention relates to certain new and
10 useful improvements in stove doors and re-
lates more particularly to means for posi-
tively retaining the stove doors in open or
closed position.

The present invention is an improvement
15 on Letters Patent Nos. 682,602 dated Au-
gust 6, 1907, and 944,475, dated December
28, 1909, which have been granted to me.

The primary object of the present invention
20 is to provide simple and economical
means for positively retaining the stove
doors in open or closed position, and further
to provide means which will allow the doors
to be opened or closed with the expenditure
of minimum force.

25 In the drawings: Figure 1 is a vertical
sectional view showing the doors in open
position; and Fig. 2 is a similar view show-
ing the doors in closed position.

An upper door A and a lower door B are
30 hinged to the stove adjacent to the top and
bottom of the oven, so as to completely close
the oven opening. A link 1 is pivoted to
the door A, and a similar link 2 is pivoted
35 to the door B. The link 1 is bowed at 3
and is pivoted at its inner end at 4 to a bar
5 which latter is pivoted at 6 to the wall C
of the oven. The pivotal point 4 of the link
1 is located below the upper end of the bar 5
40 and said upper end of the bar 5 is pivoted
at 7 to a point adjacent the free or upper
end of the link 2. A weight 8 is attached
to the free or upper end of the link 2 for a
purpose now to be described.

When the doors are in open position as
45 depicted in Fig. 1 of the drawings, the
weight occupies a position forward of the
pivotal point 6 of the bar 5 and consequently
exerts downward pressure on the link 2 and
upward pressure on the link 1 since the lat-
50 ter is pivoted to the bar 5 and the bar 5 has

downward pressure in an outward direction,
exerted thereon by reason of its being con-
nected to the link 2.

When the doors occupy closed position, as
illustrated in Fig. 2 of the drawings, the 55
weight 8 exerts downward pressure on the
link 2 and also on the upper end of the bar
5 and since the link 1 is pivotally connected
to a point on the bar 5 adjacent the upper
end of the latter, it will be seen that both 60
of the doors will be held closed by the weight
and the described connection with the doors,
which exert inward pressure on the doors.

From the above it will be seen that the
links are indirectly connected by the pivoted 65
bar 5 and that the several parts provide a
compound system of levers which in open-
ing and closing the doors obviate undue
friction and allows the doors to be opened
or closed with the expenditure of but little 70
pressure, due to the leverage provided by
the several parts.

What is claimed is:—

1. In combination with a pair of stove-
doors, a link pivoted to each door, a weight 75
on the inner end of one link, and a bar piv-
oted at its lower end to the stove and adja-
cent to the free end of the first named link,
the inner end of the other link being piv-
oted to the bar at a point between the bar 80
ends.

2. In combination with a pair of stove-
doors, a link for each door pivoted thereto,
a weight on the inner end of one link, and 85
a connection between said links and the
stove whereby when the doors are open up-
ward pressure will be exerted upon one link
and downward pressure will be exerted upon
the other link, and when the doors are closed
downward pressure will be exerted upon 90
both links to thereby exert inward pressure
upon both doors.

3. In combination with the two doors of
a stove, a system of levers connected to the
doors and a weight included in said system 95
for exerting inward pressure upon both
doors when the latter are closed and for
exerting downward pressure upon one door
and upward pressure upon the other door
when the latter are open. 100

4. In combination, with an upper and a lower oven door, a link pivoted at its outer end to the lower door and having a weight on its inner end, a bar pivoted at its lower end to the stove and also pivoted at its upper end to said link adjacent the weight thereof, and a link pivoted at its outer end to the upper door and having its lower end

10 pivoted to said bar at a point beyond the center thereof.

In testimony whereof I affix my signature in presence of two witnesses.

BERRY A. BAXTER.
